UNITED STATES PATENT OFFICE.

JOHN C. DUNTON, OF GRAND RAPIDS, MICHIGAN.

FLOORING.

1,078,776.

Specification of Letters Patent. Patented Nov. 18, 1913.

Application filed January 2, 1912. Serial No. 668,895.

To all whom it may concern:

Be it known that I, JOHN C. DUNTON, a citizen of the United States, residing at Grand Rapids, Michigan, have invented certain new and useful Improvements in Flooring, of which the following is a specification.

This invention relates to improvements in flooring.

10 The objects of this invention are to provide an improved construction of wood flooring in which the end grain of the wood is effectively presented, and the small blocks or sections are securely joined together and 15 presented in pleasing form or design, and liability of distortion or warping is overcome.

Objects relating to details and economies of construction will definitely appear from 20 the detailed description to follow.

Preferred embodiments of my invention are illustrated in the accompanying drawing, forming a part of this specification, in which:

25 Figure I is a section of flooring as made up embodying the features of my invention in its simplest form, four of the squares being here joined. Fig. II is a detail view of the assembling of the planks or boards 30 constituting one step of the process of producing my improved flooring. Fig. III indicates the method of slicing the sections from the end, which may be the next step 35 of the process in its simplest form. Fig. IV shows an additional step of the process in which the end sections are sliced into strips. Fig. V shows the next step of the process in which tapered dovetail tongues and grooves are formed on the block sections, the position of alternate strips being 40 end for end when compared with the strip as cut off. Fig. VI shows one of the complete squares made up of the blocks constituting a single square section of my improved flooring. Fig. VII is a detail cross 45 section view, showing the metal tongue and the method of tonguing and grooving between the finished squares. Fig. VIII is a modified assembling of planks or boards and 50 veneers showing a more complex form of my invention, in which special designs are produced. Fig. IX is a detail view of this complex structure sliced off lengthwise the grain with veneers applied to the sides of 55 the sliced off section, and the strip of blocks cut from the end thereof. Fig. X shows a

detail section of the flooring in this more complex form, showing the way in which the tongues and grooves are there formed.

In the drawings, similar numerals of reference refer to similar parts throughout the several views.

In Fig. I, I show a general view of a section of floor as formed according to my invention, the section there shown being made up of four complete squares. These squares are made up of blocks in such form that the ends of the grain of the wood are exposed to

view and wear and warping and distortion is avoided. I accomplish this by forming the wood into strips made up of a series of blocks 2, and half blocks 3, see particularly

Fig. I, glued or joined together. This is accomplished by piling a number of boards or planks 5—5 and a board or plank 6 of half the thickness on top of each other and forming glued joints between the same. The board of half the thickness may be either at the top or bottom. When this is done in the simplest form of my invention, I cut off

75 a slice with a cross cut saw on the line 7, producing blocks like those appearing in Fig. III, and these blocks I slice again by rip sawing on the lines 8, see Fig. III, forming the same into a series of strips as seen

75 in Fig. IV. When these strips are thus formed, I form dovetailed tongues and grooves on the opposite sides thereof, see particularly Fig. V, on a Linderman dovetailing machine, the said dovetailed tongue

9 being tapered and the corresponding dovetail groove 10 being similarly formed and tapered on the opposite side. I reverse the position of each alternate strip of

block so that in adjacent strips the half blocks 3 will be at opposite ends of the strips and the joints between the blocks will be broken between the adjacent strips. This

85 disposes the blocks so that the tendencies of the blocks to warp react the one against the other, thus insuring a flat even floor.

90 Around the outside of a square or block that is thus assembled, I insert a metal tongue 4 in a suitable narrow groove 4', which joins these sections together. The relation of

95 these parts and their grooving is indicated in Figs. VI and VII.

In the structures of Figs. VIII, IX and X, I show the method of producing fancy designs by variegated colors of the wood.

105 In joining the lumber for this complex form, I intersperse layers of veneer

11—11 between the boards 2' and 2' and 3', as seen in Fig. VIII. I then slice the same lengthwise, as indicated in Fig. VIII, and on the face of these slabs I apply an additional layer of veneer 13, see Fig. IX. I then cross cut the strips of blocks from the ends of the slab. The layer of veneer 13 is applied on the side of the block on which the dovetailed groove 15 of the strip will be formed. A dovetailed tongue 14 is formed on the opposite side of the block on which there is no veneer, and the groove 15 is of such depth as to reach through the veneer into the block beyond. 15 The relation of these parts appears very clearly in Fig. X. When the structure is assembled, it will be observed that the parts are very securely retained together by the dovetailed tongue and groove structure, and 20 that all joints are broken and each of the smaller blocks is outlined by the material, the veneer, which may be of different color or character, producing a very pleasing effect in the completed design, where the 25 parts are firmly locked as well as glued together. In either style of floor, it is probably best to cut the built-up timber lengthwise into slabs in the first instance.

It is best to form this flooring into composite squares to be assembled together. 30 The same, however, need not be put into this form, but the work of laying the same is greatly facilitated thereby.

From the description I have given, it 35 will be observed that this flooring is capable of very great variations in designs, the same producing a very effective floor in which all parts are securely joined. It will be possible to utilize waste pieces for this 40 purpose, although the production of the flooring is so economical that any lumber can be very readily and profitably used. The availability of the invention, however, for utilizing waste pieces is very apparent 45 because the end grain is utilized, and is of a good deal of advantage where the plant is engaged in a manufacture which occasions considerable waste.

Having thus described my invention,

what I claim as new and desire to secure by 50 Letters Patent is:

1. A floor construction made up of wood blocks with the grain vertical, and with the end grain exposed, the said blocks being disposed and joined together in strips 55 with layers of veneer therebetween, the strips being coupled together by tapered dovetailed longitudinal tongue and groove joints, and with a layer of veneer on the grooved side of said strips through which 60 said groove is formed and which is divided thereby, the joints between the blocks on the adjacent strips being broken to join the parts securely and overcome distortion, as specified. 65

2. A floor construction made up of wood blocks with the grain vertical and with the end grain exposed, the said blocks being disposed and joined together in strips with 70 layers of veneer therebetween, the strips being coupled together by dovetailed longitudinal tongue and groove joints, and with a layer of veneer on the grooved side of the strips through which said groove is 75 formed and which is divided thereby, the joints between the blocks on the adjacent strips being broken to join the parts securely and overcome distortion, as specified.

3. A floor construction made up of wood blocks with the grain vertical and with the 80 end grain exposed, the said blocks being disposed and joined together in strips, the strips being coupled together by tapered dovetailed longitudinal tongue and groove 85 joints, the joints between the blocks on the adjacent strips being broken to join the parts securely and overcome distortion, the position of the blocks being retained by the wedging of the tapering of the dovetail, as specified. 90

In witness whereof, I have hereunto set my hand and seal in the presence of two witnesses.

JOHN C. DUNTON. [L.S.]
